(57) **CLAIM**

The ornamental design for a mobile cleaning robot, as shown and described.

DESCRIPTION

FIG. 1 is a top-front-left-perspective view of our mobile cleaning robot with a pad assembly in a stored position;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof;

FIG. 8 is a bottom-rear-left-perspective view thereof; and

FIG. 9 is a top-rear-right-perspective view thereof.

FIG. 10 is a top-front-left-perspective view of our mobile cleaning robot showing the pad in the state of use;

FIG. 11 is a front view thereof;

FIG. 12 is a rear view thereof;

FIG. 13 is a right-side view thereof;

FIG. 14 is a left-side view thereof;

FIG. 15 is a top view thereof;

FIG. 16 is a bottom view thereof;

FIG. 17 is a bottom-rear-left-perspective view thereof; and,

FIG. 18 is a top-rear-right-perspective view thereof.

The broken lines shown in the figures is for the purpose of illustrating portions of the mobile cleaning robot that form no part of the claimed design.
